CLAIM

The ornamental design for a combined holder for sliced bread and condiment containers or the like, as shown and described.

DESCRIPTION

FIG. 1 is a top perspective view of a combined holder for sliced bread and condiment containers or the like, showing my new design;

FIG. 2 is a top plan view of FIG. 1;

FIG. 3 is a side elevation of FIG. 1;

FIG. 4 is an end elevation of FIG. 1; and

FIG. 5 is a bottom plan view of FIG. 1.

FIG. 1

FIG. 2

FIG. 3

FIG. 4

FIG. 5
